UNITED STATES PATENT OFFICE

121,669

DESIGN FOR AN AUTOGRAPHIC REGISTER CASING

Robert Davol Budlong, Chicago, Ill., assignor to United Autographic Register Co., a corporation of Illinois

Application April 22, 1940, Serial No. 91,869

Term of patent 7 years

To all whom it may concern:

Be it known that I, Robert Davol Budlong, a citizen of the United States, residing at Chicago, county of Cook, and State of Illinois, have invented a new, original, and ornamental Design for an Autographic Register Casing, of which the following is a specification, reference being had to the accompanying drawing, forming a part thereof, in which:

Figure 1 is a side elevational view of an autographic register casing showing my new design; Figure 2, a plan view; Figure 3, a front elevational view; and Figure 4, a rear elevational view thereof.

I claim:

The ornamental design for an autographic register casing, as shown.

ROBERT DAVOL BUDLONG.
